FOLDING STAIRS

Ernest E. Pierce, Dallas, Tex.

Application July 15, 1949, Serial No. 104,840

5 Claims. (Cl. 228—50)

1

This invention relates to folding stairs and more particularly to sectional staircase especially useful in gaining access to building attics.

The principal object is to provide a sectional stairway having a primary and a secondary spring counterbalance, the former acting through the medium of an eccentric pulley or cam to exert a force tending to move the hinged sections of the stairway towards folded position to minimize the extending and folding effort, while the secondary counterbalance serves the dual purpose of resisting the effort to displace the subsection with respect to the main section of the stair both in the folding and extending operations. Moreover, and cooperating with the secondary counterbalance is a cable connected between the eccentric actuating arms of the main stair section and selected supporting arms of the subsection and is effective to exert a force tending to maintain axial alignment of the pivoted sections of the eccentric actuating arm when the stair sections are in extended position.

Other and lesser objects will become apparent as the description proceeds, taken in connection with the accompanying drawing, wherein:

Figure 1 is a perspective view of a folding stairway embodying the invention, shown in extended position.

Figure 2 is a side elevational view thereof in folded position.

Figure 3 is a side elevational view in partly extended position and showing in dotted lines the full extended position thereof.

Figure 4 is a fragmentary side elevational view showing one of the eccentrics in detail.

Figure 5 is a sectional view taken on line 5—5 of Figure 4, and

Figure 6 is a sectional view taken on line 6—6 of Figure 3.

Continuing with a more detailed description of the drawing, reference numeral 10 denotes fragmentarily a floor and ceiling construction in which is made an opening to accommodate the stair, the opening being defined by a suitable frame 11.

The stairway is made up of two or more sections, depending upon the height of the ceiling from the floor and the section which is joined to the frame 11 is referred to herein as the main stair section 12 and consists of the side members between which are spaced the treads 13. The main section 12 is pivotally connected to the frame 11 by means of curved straps 14, one being affixed to each of the side members of the section and extending through slots 15 (Figs. 3 and 6) in

2

an end of the frame and engaging pins journaled in bearings 16, mounted on the outer surface of the end members of the frame. Affixed to the underside of the main section 12 is a cover 17 which is adapted to close the opening in the ceiling when the stair sections are raised to folded position.

The ends of the side members of the main stair section 12, opposite the hinge, are each obliquely formed to conform to the similarly formed ends of the side members of a sub-section 18, and which are joined to the end of the main section through the medium of a pair of arms 19 on each side of the stair. Each pair of arms are pivoted to plates 20 affixed to the side members of each stair section and which are each provided with longitudinally aligned holes for adjustably receiving the pivot bolts of the arms 19. The particular manner of attaching the arms 19 to the respective stair sections insures parallelism of the arms in any and all positions of the stair sections, as shown.

The primary counterbalance of the stairway consists of a pulley or peripherally grooved wheel 21, eccentrically mounted on a stub shaft 22 which latter is journaled in a bearing 23, affixed to the top of a side member of the frame 11. An identical arrangement is provided on the opposite side of the frame.

The cam wheels or eccentrics 21 operate in recesses 24 made therefor in the outer surfaces of the frame side members and on the inner end of each shaft 22 is affixed the upper end of the upper section 25 of an arm which will be referred to herein as the eccentric actuating arm. The section 25 of the arm is pivoted at 26 to a lower section 27 and the lower end of this section, in turn, is pivoted adjustably to a plate 28, affixed to the outside of one of the side members of the main stair section 12, adjacent the end opposite its hinge.

Anchored to brackets 29 at the hinged end of the stair are the ends of main counterbalance springs 30 which extend along the tops of the frame side members and to the opposite end of each of these springs is affixed the end of a cable 31. The opposite end of the cable is secured at 32 (Fig. 4), a selected point in the periphery of the eccentric wheel 21, so that the cable will follow in the groove of the wheel as the latter revolves during raising and lowering movements of the main stair section.

It is apparent from the foregoing that as the main section 12 is lowered, the sections 25 and 27 of the eccentric actuating arm will move towards axially aligned position and in so moving, the

wheel 31 will rotate in a clockwise direction to wind the cable 31 thereon, thus storing energy in the springs 30 effective to nearly balance the weight of the stair sections 12 and 18. A cross-member 33 underlying the strap hinges 14 of the main section 12 constitutes a stop and is positioned to determine the angle of the section 12 in lowered position.

On each side of the stair sections there is provided a coil spring 34 of less strength than the spring 30 and is connected at one end to a plate 35, affixed to a side section of the main stair section and at its opposite end at 36 to the lowest of the two parallel arms 19 which constitute the support for the sub-section 18. The springs 34 are connected to the arms 19 at an appropriate point to exert a force tending to resist downward displacement of the sub-section 18 and constitutes the secondary counterbalance herein referred to. The presence of these springs in the assembly minimizes the effort required to move the sub-section into and out of folded relationship with its companion section.

When the stair is in folded position, as exemplified in Figure 2, the main section 12 is moved to the position shown in dotted lines in this figure by pulling downwardly on the short length of cord 37, depending from an end thereof. This is the initial step in the operation of unfolding the sections. When lowered, the main section brings with it the sub-section 18 but the latter is held against downward displacement by the action of springs 34 until the lower end of the sub-section is grasped and pulled to a position where its weight will overcome the resistance of the springs 34, whereupon it will swing under control of these springs into axial alignment with the main section 12, as in Figure 1.

As the sections assume axial alignment as explained above, a cable 38, connected to and extending between the eccentric actuating arm and one of the sub-section supporting arms 19, is brought under tension and imposes a force on the upper sections 25 of the eccentric actuating arm, tending to bring it into longitudinal alignment with the companion section 28 thereof, thus to overcome any tendency of the springs 30 to raise the foot of the stairs off the floor. In other words, the cables 38, being joined to the eccentric actuating arms at one end and at their other ends to arms 19, after passing over pulleys 39, affixed to the side members of the main section 12, are effective to maintain dead center relationship of the pivoted sections of the eccentric actuating arms and thus lend stiffness thereto as long as the stair sections are in extended position but the force so exerted by the cables 38 is not such that it cannot be overcome simply by lifting upward on the sub-section 18 and thus releasing both stair sections to the force of the primary and secondary counterbalancing springs 30 and 34 respectively which, while minimizing the load, are not wholly adequate to restore the stair sections to folded position in the ceiling opening.

Each of the side members of the main stair section 12 has a hand rail 40 mounted thereon. It will also be observed, especially in Figure 1, that the ends of the side members of the sub-section 18 each carries a guide plate 41 which is brought to bear against the side members of the main section 12 when the ends of the side members of the sections are brought into juxtaposition in extended position of the stair and serve as stabilizers, holding the sections in alignment.

Manifestly, the construction as shown and de-

scribed is capable of some modification and such modification as may be construed to fall within the scope and meaning of the appended claims is also considered to be within the spirit and intent of the invention.

What is claimed is:

1. A folding stairway comprising a horizontal frame, a main stair section pivoted at one end to an end of said frame and adapted to be disposed inoperatively within the confines of said frame, a sub-stair section, a pair of parallel arms on each side of said stair sections for pivotally supporting said sub-stair section on said main stair section, a toggle on each side of said frame, each comprising a link pivoted at one end to one side of said main stair section, and an arm pivoted at one end to the opposite end of said link, an eccentric pulley mounted on each side of said frame, to the shaft of which the opposite end of said latter arm is affixed to move therewith, a primary counterbalancing spring on each side of said frame, said springs having their ends attached to the peripheries of said pulleys and their opposite ends to an end of said frame to exert a lifting force on said stair sections through said eccentric pulleys and said toggle, a pair of secondary counterbalancing springs having their upper ends connected to the sides of said main stair sections and their lower ends to one of said parallel arms and effective to exert a lifting force on said sub-stair section and flexible means for stabilizing said toggle in extended position of said stair sections.

2. A folding stairway including a horizontal frame, a main stair section pivoted at one end to an end of said frame for movement into extended and inoperative positions, a sub-stair section supported by and movable into extended and inoperative position on said main stair section, an eccentrically mounted wheel on each side of said frame, a pair of primary counterbalancing springs connected to the frame at one end, a wire line connected at one end to each of said counterbalancing springs, said wire lines being connected to and partially wound on the peripheries of said wheels, a toggle on each side of said stairway comprising a link pivoted at one end to the main stair section and an arm pivoted at one end to the opposite end of said link and affixed at its other end to an axle of one of said eccentric wheels to rotate the latter as said stair sections are actuated under the influence of said spring counterbalance tending to urge said stair sections toward inoperative confinement in said frame, a pair of secondary counterbalance springs tending to urge the sub-stair section towards folded relationship on said main stair section and flexible means adapted to urge the arm and link of said toggle into longitudinal alignment as said stair sections are moved to extended position to stabilize said stair sections in said extended position.

3. A folding stairway including a frame, a main stair section and a sub-stair section, the latter being superimposed on the main stair section in inoperative position and disposed in axial alignment thereof in extended position of said sections, an eccentrically mounted wheel on each side of said frame, a toggle on each side of said stairway, said toggles each consisting of a link having its lower end pivoted to the lower end of said main stair section and an arm pivoted at one end to said link, the upper end of said arm being affixed to the axles of said wheels to actuate the same when said stair sections are moved, a pair of primary counterbalance springs, an end of each

being anchored to an end of said frame, each having a wire line connected thereto, the opposite ends of said wire lines being connected to and partially wound on said wheels to resist rotation thereof during lowering movement of said stair sections, a pair of parallel arms pivotally connecting said main and sub-stair sections, spring means connecting said main and sub-stair sections for resisting movement of said sub-stair section towards extended position and means for connecting each arm of said pair of parallel arms with an arm of each of said toggles for stabilizing said stair sections in extended position.

4. A folding stairway including a horizontal frame, a main stair section pivoted at one end to an end of said frame, a hand rail mounted on and spaced from each side of said main stair section, a sub-stair section, a pair of parallel arms pivoted at their ends to said main and sub-stair sections to support said sub-stair section for swinging displacement into extended relationship with said main frame section and to dispose said sub-stair section above said hand rails in folded position of said stair sections, a counterbalance spring on each side of and connecting said stair sections to resist movement of the sub-stair section towards extended position, a toggle on each side of said main stair section comprising a link having its lower end pivoted to said main stair section and an arm pivoted to the upper end of said link, an eccentric wheel on each side of said frame, means fixedly connecting the upper end of the arms of said toggle to the axles of said eccentric wheels, a second counterbalance spring on each side of said frame, one end being anchored to an end of said frame, wire lines affixed at their ends to the ends of said springs and having their opposite ends affixed to said eccentric wheels to resist rotation thereof as imposed by said sectional arms during movement of said

40

stair sections towards extended position and means connecting an arm of each pair of said parallel arms to the arm of each of said toggles for stabilizing said stair sections in extended position.

5. A folding stairway comprising a horizontal frame, a pair of relatively pivoted stair sections, one of which is pivoted at one end to an end of said frame, hand rails on said latter stair section, a pair of parallel arms on each side of said main stair section supporting the companion stair section for movement to a position above said hand rails and to an extended position in relation to the first of said stair sections, spring means resisting displacement of the companion stair section to extended position, a wheel mounted eccentrically on an axle at each side of said frame, a toggle on each side of said stair sections, the lower ends of said toggles being pivoted to the first of said stair sections and affixed at their opposite ends to said wheel axles, springs affixed at their ends to an end of said frame, wire lines affixed at their ends to the ends of said springs and at their opposite ends to the peripheries of said wheels to resist rotation thereof during movement of said stair sections to extended position and means connecting one of each pair of said parallel arms with each said toggles for stabilizing said stair sections in extended position.
